UNITED STATES PATENT OFFICE.

WILLIAM R. McKEEN, JR., AND JAMES H. GROVE, OF OMAHA, NEBRASKA.

LOCOMOTIVE ASH-PAN.

1,059,059.

Specification of Letters Patent. Patented Apr. 15, 1913.

Application filed July 16, 1907. Serial No. 383,972.

To all whom it may concern:

Be it known that we, WILLIAM R. McKEEN, Jr., and JAMES H. GROVE, residing at Omaha, in the county of Douglas and State 5 of Nebraska, have invented certain new and useful Improvements in Locomotive Ash-Pans, of which the following is a full, clear, and exact description, such as will enable others skilled in the art to which it appertains to make and use the same.

This invention relates to ash-pans and, with regard to the more specific features thereof, to ash-pans of railway locomotives.

One of the objects thereof is to provide an 15 efficient and practical ash-pan in which the chance of dropping hot coals is eliminated.

Another object is to provide a durable and inexpensive ash-pan in which warping or burning out is done away with.

20 Another object is to provide a construction of the above nature in which full and free draft is provided without chance of blowing live coals or cinders through the air inlet openings.

25 Other objects will be in part obvious and in part pointed out hereinafter.

This invention accordingly consists in the features of construction, combinations of elements and arrangement of parts which 30 will be exemplified in the construction hereinafter set forth, and the scope of the application of which will be indicated in the following claims.

In the accompanying drawings, wherein 35 is shown one of various possible embodiments of this invention,—Figure 1 is a side elevation thereof, certain parts being cut away in order to show the construction more clearly; and Fig. 2 is an end view also partially in section.

Similar reference characters refer to similar parts throughout both views of the drawings.

40 As tending to cast light upon certain features of this invention, it may here be noted that there is a tendency in ash-pans, and particularly those of the locomotive type, to warp or burn out by reason of the hot coals and cinders falling therein, which often 45 work up a considerable fire in this part of the locomotive. This is particularly the case when air is admitted to the lower portion of the ash-pan on account of the strong draft due to high winds or the motion of the locomotive. Any warping or other deformation 50 tends to permit the dropping of live coals,

with a tendency to set fire to wooden trestles or bridges, and such fires often occur with an ash-pan of the widely used types, even with the pan in good condition, by reason of 60 the blowing of hot coals or cinders through the air-inlet openings. The above and other defects are eliminated in constructions of the nature of that hereinafter described.

Referring now to Fig. 1 of the accompanying drawings, there is shown an ash-pan the upper portion 1 of which is formed upon a framing formed of the angle irons 2, upon which the mud-ring of the boiler rests, and lower angle irons 3, the body of the pan 70 being constituted of boiler steel and the parts riveted together as indicated in the drawings. About the sides and end of this portion of the ash-pan are formed air inlet ports 4; the outer ends of which are guarded by upwardly flared shields 5, preferably likewise formed of sheet metal. The lower portion of the ash-pan comprises the sections 75 6 and 7, spaced, as indicated in the drawings, in the well-known manner in order to 80 accommodate the driver axle. The forward portion comprises the upper angle iron 8, to which are secured depending angle irons 9 and 10 of the curved conformation indicated in Fig. 2 of the drawings. The section 7 is, 85 in general, similar to section 6 having the upper angle irons 11 and the curved angle irons 12 and 13 depending therefrom, and the body of both of these sections is formed of boiler iron as in the case of the upper 90 portion of the pan, being riveted to the angle iron frame-work and thus given a general semi-cylindrical form which possesses a high degree of mechanical strength and is substantially proof against warping in use. 95 Sections 6 and 7 are provided with the ash-doors 14 and 15 having lining plates 23, each of which is hinged as at 16 and is normally secured in tightly closed condition as by the pin 17 and key 18. These sections are thus, 100 in normal use, substantially imperforate although means may be provided, if desired, as at 19, for an ash-pan blower should the same be used. Angle irons 8 and 11 are tightly held against the bottom angle irons 105 3 of the upper portion of the pan, as by the pins 20, provided with split keys 21, thus insuring a tight and secure joint and yet permitting the removal of the lower sections if desired.

110 The method of use of the above-described embodiment of this invention is substan-

tially as follows: Upon cinders or hot coals falling into the ash-pan they drop into the lower portion thereof, which is sealed and forms thus a dead air space in which all fire 5 is quickly extinguished. Any heat, moreover, which may be generated in this portion of the pan can work no harmful effect inasmuch as no appreciable warping of the curved sheets can occur and the doors are 10 thoroughly protected by the liners as above set forth. No openings nor crevices obtain, moreover, through which heated particles can be dropped or blown, as is the case in former ash-pan constructions in which it 15 has been unsuccessfully attempted to protect the openings by screens and the like. The draft is supplied to the grate through the air ports 4 and, by reason of the conformation of the shields 5, is forced inwardly in 20 a downward direction and thence passes upwardly to the fire-box. In this manner, even though a considerable degree of air pressure arises in the ash-pan, no particles can be blown through the air inlets as the 25 incoming air rushes in a downward direction, tending to force all solid matter to the lower portion of the pan.

It will thus be seen that there is provided a construction in which the several objects 30 of this invention are achieved, and that the same is cheap, strong and durable and of an essentially practical nature. The parts are quickly assembled or taken apart and are so formed and disposed as not only efficiently to perform their functions in the matter of retaining and extinguishing live 35 coals and providing abundant draft to the grate, but as a whole to possess a high degree of mechanical strength and be capable 40 of a long life in use.

As many changes could be made in the above construction and many apparently widely different embodiments of this invention could be made without departing from 45 the scope thereof, it is intended that all matter contained in the above description or shown in the accompanying drawings shall be interpreted as illustrative and not in a limiting sense.

50 The essential features and combination of the invention will be particularly set forth in the claims, and these are not to be limited to the particular structure illustrated, but are intended to include generally such modifications and substitutions of equivalents as reasonably fall within the scope of the invention.

Having described our invention, what we claim as new and desire to secure by Letters Patent is:—

1. In an ash-pan the combination of an

upper portion formed of sheet metal and provided with angle bars at its upper and lower edges; a lower portion formed of sheet metal and provided with angle bars at its 65 upper edges; and means adapted to secure the upper angle bars of said lower portion to the lower angle bars of said upper portion and form a substantially tight joint therebetween, said lower portion being in 70 normal operative condition substantially imperforate and said upper portion being provided with air inlet ports and having secured thereon sheets adapted to guide the entering air in a downward direction. 75

2. In an ash-pan, the combination of an upper portion open at its lower side; a depending lower portion closed at its bottom and sides and making a close joint with the upper portion; separable connections between said upper and lower portions; a door in one end of said lower portion; and inlet air ducts leading the incoming air in a downward direction through the walls of said upper portion. 80

3. In an ash-pan, the combination of an upper portion open at its lower side; depending lower portions closed at their bottoms and sides and making close joints with the upper portion; separable connections between the upper and said lower portions; doors, a door being located in one end of each of said lower portions; and inlet air ducts adapted to conduct incoming air in a downward direction through the walls of 95 said upper portion.

4. In an ash-pan, the combination of an upper portion open at its lower side; substantially semi-cylindrical lower portions making close joints with the upper portion; 100 separable connections between said upper and lower portions; doors, a door being located in one end of each of said lower portions; and air ducts located in said upper portion and adapted to direct incoming air 105 in a downward direction.

5. An ash-pan comprising an upper section provided with air inlets and adapted to direct the incoming air in a downward direction; and a lower section adapted to receive and contain the hot ashes; and removable connections between said sections whereby the lower section may be removed for repair or replacement without disturbing the upper section. 110

In testimony whereof we affix our signatures, in the presence of two witnesses.

WILLIAM R. McKEEN, JR.
JAMES H. GROVE.

Witnesses to both signatures:
